P. KELLER

REED FOR WIRE MESH MAKING

Filed June 4, 1925

INVENTOR
P. Keller

BY
J. Ledermann
ATTORNEY

UNITED STATES PATENT OFFICE.

PETER KELLER, OF BROOKLYN, NEW YORK.

REED FOR WIRE-MESH MAKING.

Application filed June 4, 1925. Serial No. 34,779.

The main object of this invention is to provide a reed for crimping the cross strings of woven wire. From experience, it has been found that the warp strings of a wire mesh are easily fractured by various strains of the mesh. It has also been found that crimping the cross strings as they pass between the warp strings makes a wire mesh much less liable to having its warp strings fractured. 10 To accomplish this crimping of the cross strings, the novel type of reed illustrated herein is provided.

The above and other objects will become apparent in the description below, in which 15 characters of reference refer to like-named parts in the drawing.

Referring briefly to the drawing, Figure 1 is a front elevational view of a section 20 of the reed, showing the groove or channel in its most desirable position on the reed.

Figure 2 is a sectional elevational view taken on line 2—2 of Figure 1.

Figure 3 is a perspective view of a number 25 of reed blades, showing the particular method of aligning the cut-out portions to form a V-shaped groove.

Figure 4 is an illustration showing the position of the crimping device preparatory 30 to its use on a weft string.

Referring in detail to the drawing, the 35 numeral 10 indicates the warp strings of some rigid material such as wire which is interlaced with cross strings 11 by weaving the warp strings and cross strings in the manner shown. These warp strings are easily fractured, due to their great length, especially when used as filters in paper making machinery, in which a wire mesh is used up to a length of three hundred feet.

40 By crimping the cross strings, as shown at 12, it has been found that the warp strings are not as easily fractured. To accomplish crimping in the cross strings illustrated, the reed illustrated in Figures 1, 2, and 3, is provided. This reed consists of a plurality 45 of blades 13 which are rectangular in outline and are provided with spaces 14 between them, said spaces being the thickness of the blade. Into these spaces 14, the 50 warp strings 10 are inserted when the wire

mesh is being woven. These blades are laid upon a steel block 15 and are formed into a reed by securing said blades between pairs of retainer bars 16. Each of the reeds has a semi-circular cut-out portion 17. These cut-out portions are off-set on the reeds in such manner that the vertex or intersecting edges of the semi-circular cut-out portions form a V-shaped groove 18 into which groove the cross strings of the wire mesh 55 weave are adapted to be pulled. These semi-circular cut-out portions are so positioned on the blades that one semi-circular cut-out portion on one blade is off-set half of the diameter of the cut-out portion on the next 60 adjacent blade, as illustrated in Figure 2.

In crimping the cross strings of a wire mesh, the warp strings 10 are inserted into the spaces 14 between the blades 13. As a cross string 11 is woven into the wire mesh 70 by passing said cross string under and over successive warp strings, the cross string is drawn or pulled toward the V-shaped groove 75 of the reed. Contact with the intersecting portion of the groove crimps the cross 75 wire between the warp strings, the crimping being illustrated in Figure 4.

I claim:

1. In a reed for crimping the cross strings of a wire mesh, a plurality of spaced-apart 80 blades, said blades permitting insertion of warp strings therebetween, the blades having semi-circular cut-out portions, said cut-out portions being off-set vertically and alternately to produce a series of crimps in 85 the weft in the vertical plane for intimate engagement with the warp wires.

2. In a reed for crimping the cross strings of a wire mesh, a plurality of spaced-apart 90 blades, said blades permitting insertion of warp strings therebetween, the blades having semi-circular cut-out portions, said cut-out portions being off-set vertically and alternately to produce a series of crimps in 95 the weft in the vertical plane for intimate engagement with the warp wires, the semi-circular cut-out portions on alternate blades being aligned.

3. In a reed for crimping the cross strings of a wire mesh, a plurality of spaced-apart 100

blades, said blades permitting insertion of warp strings therebetween, the blades having semi-circular cut-out portions, said cut-out portions being off-set vertically and alternately to produce a series of crimps in the weft in the vertical plane for intimate engagement with the warp wires, the semi-

circular cut-out portions on alternate blades being aligned, the semi-circular cut-out portions of the blades forming a substantially 10 V-shaped notch.

In testimony whereof I affix my signature.

PETER KELLER.
